UNITED STATES PATENT OFFICE.

ALEXANDER BIELAWSKI, OF BAYONNE, NEW JERSEY.

LIFE-SAVING BOAT.

1,295,681.

Specification of Letters Patent.

Patented Feb. 25, 1919.

Application filed June 8, 1918. Serial No. 238,859.

To all whom it may concern:

Be it known that I, ALEXANDER BIELAWSKI, a citizen of Russia, residing at Bayonne, county of Hudson, and State of New Jersey, have invented certain new and useful Improvements in Life-Saving Boats, of which the following is a specification.

This invention relates to improvements in boats, and particularly to types adapted to be used in rough water for life saving and like purposes.

The principal object of the invention is to provide a boat of this type with buoyant floats secured to and extending at a distance from the sides thereof, and which effectively prevents the boat from capsizing.

A further object is to provide means for adjusting the floats to the sides of the boat and maintaining them in rigid relation.

These and other like objects are attained by the novel construction and combination of parts hereinafter described, and shown in the accompanying drawing, forming a material part of this disclosure, and in which:—

Figure 1 is a top plan view showing the preferred form of the means of attaching the floats to the boat, and,

Fig. 2 is a transverse sectional view taken on line 4—4 of Fig. 1.

As shown, the floats 20 are held within bands 19, which are engaged at their parallel, bent ends by pins 28, with bars 30, extending toward the boat and which are held by other pins 31 in blocks 32, slidably mounted upon rails 33, fixed in angular brackets 34, secured to the hull of the boat at its upper edge in the manner of a hinge, whereby the floats may be raised or lowered with relation to the upper surface of the boat.

In order to maintain the bars 30 in proper relative positions, near their outer ends straps 36 provided with holes are secured, and other straps 37, secured with one end to the keel of the boat are guided therefrom

so as to cross each other. The ends of the straps 37 are provided with buckles 38 adapted to engage with their tongues the holes in the straps 36 for allowing an adjustment of the relative positions of the bars 30 and 50 the floats and boat.

In this latter form of construction, the buoyant elements or floats 20 may preferably be filled with cork or like light material 39 so that should leakage occur they will 55 still remain in a buoyant condition.

From the foregoing it will be seen that in addition to sliding the blocks 32 on the rails 33, it is also possible to disconnect the floats and fold the arms 30 alongside the 60 rail as indicated in the broken lines in Fig. 1.

A cover 45 of flexible water-proof fabric may be used over the boat, the same being supported by curved rods 46, as indicated in 65 Fig. 2.

Thus it will be seen that means have been provided whereby the boat cannot overturn laterally and that the device can be attached to boats of the ordinary type of construction 70 in a ready manner.

Having thus described my invention what I claim as new and desire to secure by Letters Patent, is:

In a life boat, the combination with the 75 frame thereof, and a pair of non-sinkable floats, of a pair of rails secured at their ends upon opposite sides of said boat, bars hingedly engaged with said rails extending in parallel horizontally therefrom, bands 80 encircling said floats, said bands being pivotally engaged with the ends of said extending bars, pairs of straps having one of their ends engaged with said bands and the other with the keel of the boat, and buckles on 85 said straps whereby their opposite length may be lengthened or shortened.

In testimony whereof I have affixed my signature.

ALEXANDER BIELAWSKI.

Copies of this patent may be obtained for five cents each, by addressing the "Commissioner of Patents, Washington, D. C."
